UNITED STATES PATENT OFFICE.

ERIC A. STARKE, OF BERKELEY, CALIFORNIA.

APPARATUS FOR SAVING GAS AND OIL FROM PRODUCING WELLS

Application filed November 27, 1922. Serial No. 603,455.

To all whom it may concern: Be it known that I, ERIC A. STARKE, a citizen of the United States, residing at Berkeley, in the county of Alameda and the State of California, have invented certain new and useful Improvements in Apparatus for Saving Gas and Oil from Producing Wells, of which the following is a specification.

My invention relates to apparatus for separating the gas from the oil, and saving both in connection with producing wells in which both oil and gas occur. My present invention particularly relates to and consists in improvements upon that apparatus previously patented by me under No. 1,040,806, dated October 8th, 1912, to which patent reference is hereby made. These improvements comprise a novel relative arrangement and connection of the bend separating members, and a novel means for introducing the well product. The objects of said improvements are to provide for a more effective separation, and to introduce the well product under conditions which conduce to an immediate and quiet initiation of the operation, by avoiding swirl, due to its high pressure, which tendency may result in such violent agitation as to cause in some cases an emulsification of the gas and oil prohibitive of separation.

The accompanying drawings which illustrate my improved apparatus show Fig. 1 is an elevation of the apparatus. Fig. 2 is a plan of the same. Fig. 3 is an elevation of the outlet end. Fig. 4 is an elevation of the inlet end. Fig. 5 is a cross section, enlarged, on the line 5—5 of Fig. 2.

1 is a relatively long, recumbent conduit, say, for example, a 10 inch pipe, constituting the initial separating member. As shown in Fig. 1, this pipe lies at a slight inclination to the horizontal, indicated by the ground line A—A.

2 is a second relatively long recumbent conduit lying to one side of the first conduit and at an inclination to the horizontal in the same direction. This conduit may for the sake of example, be a pipe 4 inches in diameter, and said pipe constitutes an auxiliary separating member.

3 is a relatively long recumbent conduit, say, for example, a pipe 6 inches in diameter. It lies to one side of the other con-

duits, but at an inclination to the horizontal reversed to their inclination. It constitutes both a final separating member and

Pipes 4 connect the separating pipes 1 and 2, at intervals from their higher end for a portion of their length. These pipes lead from the upper cross sectional area of

pipe 1, into the upper cross sectional area of pipe 2, and are subject to control by means of valves 5.

There is also a connection between the pipes 1 and 2, near their lower ends, by means of the pipe 6, controlled by a valve 7.

This connection may be used to return oil from pipe 2 to pipe 1.

The lower end of the gas receiver pipe 3 which connects with the higher end of the auxiliary separating pipe 2, by means of a

relative arrangement and connection of the bend 8.

The outlet end of pipe 1 has a controllable bottom discharge 9 and a controllable end discharge 10. The outlet end of pipe 2 has a controllable end discharge 11. The

outlet end of receiver pipe 3 has a controllable end discharge 12. All these discharges lead to oil storage tanks, not shown,

or to some other suitable destination for the oil.

The gas receiver pipe 3 is provided near its outlet end with a controllable pipe 13 leading to a gas main, not shown, and said pipe 13 is fitted with a safety valve 14.

In the accompanying drawings which illustrate my improved apparatus, Fig. 1 is a pressure dial in the receiver pipe 3, and 16 is a reading glass in the separator

Fig. 2 is an elevation of the apparatus. Fig. 3 is a plan of the same. Fig. 4 is an elevation of the outlet end. Fig. 5 is an elevation of the inlet end.

Fig. 6 is a cross section, enlarged, on the line 5—5 of Fig. 2.

1 is a relatively long, recumbent conduit, say, for example, a 10 inch pipe, constituting the initial separating member. As shown in Fig. 1, this pipe lies at a slight inclination to the horizontal, indicated by the ground line A—A.

2 is a second relatively long recumbent conduit lying to one side of the first conduit and at an inclination to the horizontal in the same direction. This conduit may for the sake of example, be a pipe 4 inches in diameter, and said pipe constitutes an auxiliary separating member.

3 is a relatively long recumbent conduit, say, for example, a pipe 6 inches in diameter. It lies to one side of the other con-

duits, but at an inclination to the horizontal reversed to their inclination. It constitutes both a final separating member and

Pipes 4 connect the separating pipes 1 and 2, at intervals from their higher end for a portion of their length. These pipes lead from the upper cross sectional area of

pipe 1, into the upper cross sectional area of pipe 2, and are subject to control by means of valves 5.

There is also a connection between the pipes 1 and 2, near their lower ends, by means of the pipe 6, controlled by a valve 7.

This connection may be used to return oil from pipe 2 to pipe 1.

The lower end of the gas receiver pipe 3 which connects with the higher end of the auxiliary separating pipe 2, by means of a

relative arrangement and connection of the bend 8.

The outlet end of pipe 1 has a controllable bottom discharge 9 and a controllable end discharge 10. The outlet end of pipe 2 has a controllable end discharge 11. The

outlet end of receiver pipe 3 has a controllable end discharge 12. All these discharges lead to oil storage tanks, not shown,

or to some other suitable destination for the oil.

The gas receiver pipe 3 is provided near its outlet end with a controllable pipe 13 leading to a gas main, not shown, and said pipe 13 is fitted with a safety valve 14.

In the accompanying drawings which illustrate my improved apparatus, Fig. 1 is a pressure dial in the receiver pipe 3, and 16 is a reading glass in the separator

Fig. 2 is an elevation of the apparatus. Fig. 3 is a plan of the same. Fig. 4 is an elevation of the outlet end. Fig. 5 is an elevation of the inlet end.

Fig. 6 is a cross section, enlarged, on the line 5—5 of Fig. 2.

1 is a relatively long, recumbent conduit, say, for example, a 10 inch pipe, constituting the initial separating member. As shown in Fig. 1, this pipe lies at a slight inclination to the horizontal, indicated by the ground line A—A.

2 is a second relatively long recumbent conduit lying to one side of the first conduit and at an inclination to the horizontal in the same direction. This conduit may for the sake of example, be a pipe 4 inches in diameter, and said pipe constitutes an auxiliary separating member.

3 is a relatively long recumbent conduit, say, for example, a pipe 6 inches in diameter. It lies to one side of the other con-

supply pipe 17, as herein shown, the velocity of the entering product is so reduced, that while the gas passes readily through the supply pipe, a considerable portion of the liquid and solid components, such as sand 5 pass through the slit and break up the swirling tendency, so that a condition of relative quiet is gained much sooner than would be possible otherwise. I have, in practice, 10 found this slotted supply pipe very effective, and in this connection wish to point out that such a feed pipe is available in the separating art whether used with an apparatus such as here shown and with the particular product 15 herein described, or in connection with the separation of other aggregates of a gaseous, liquid and solid nature.

The separation of the gas from the oil and the other components such as sand takes 20 place in the attenuated chamber of the pipe 1, supplemented by a like effect in pipes 2 and 3 and from these pipes the separated materials may be continuously withdrawn, as in my former patented device. But in 25 the present improved arrangement, I find the result is heightened, both by having the connections 5 between the pipes 1 and 2 extend only for a portion of their length, instead of, as formerly, for their entire length, 30 thus providing greater zones of quiet; and by having the gas receiving pipe at an inclination to the reverse of the other pipes, which arrangement gives the gas a greater freedom of flow to its discharge.

35 I claim: —

1. An apparatus for the described purpose, comprising a recumbent separating pipe; a supply pipe leading from a source of aggregate under pressure, and fitting tightly 40 through one end of the separating pipe, said supply pipe extending within said separating pipe and being longitudinally slotted in the bottom of its said extending portion; a delivery pipe leading from the upper cross 45 sectional area of said separating pipe for carrying off the gaseous component of the aggregate; and means for discharging the liquid component from the lower cross sectional area of said separating pipe.

2. An apparatus for the described purpose, comprising a plurality of recumbent separating pipes, lying at an inclination in the same direction; a plurality of pipes connecting successively the upper cross sectional areas of said pipes, at intervals throughout 55 a portion of the length of said separating pipes at their higher ends, for passing the gaseous component from one separating pipe to the next; a final recumbent pipe lying at an inclination the reverse of that of the 60 separating pipes and connected at its lower end with the higher end of the last of said separating pipes, for receiving the gaseous component therefrom, a supply pipe leading from a source of aggregate under pressure 65 and fitted tightly through to the higher end of the first of said separating pipes; and means for discharging the liquid component of the aggregate from the lower cross sectional areas of said recumbent pipes. 70

3. An apparatus for the described purpose, comprising a plurality of recumbent separating pipes, lying at an inclination in the same direction; a plurality of pipes connecting successively the upper cross sectional areas of said pipes, at intervals throughout 75 a portion of the length of said separating pipes at their higher ends, for passing the gaseous component from one separating pipe to the next; a final recumbent pipe lying at 80 an inclination the reverse of that of the separating pipes and connected at its lower end with the higher end of the last of said separating pipes, for receiving the gaseous component therefrom; a supply pipe leading 85 from a source of aggregate under pressure and fitted tightly through the higher end of the first of said separating pipes, said supply pipe extending within said first separating pipe and being longitudinally slotted in 90 the bottom of its said extending portion; and means for discharging the liquid component of the aggregate from the lower cross sectional areas of said recumbent pipes. 95

In testimony whereof I have signed my name to this specification.

ERIC A. STARKE.
